UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

HEELING-MACHINE.

1,384,870.

Specification of Letters Patent. Patented July 19, 1921.

Application filed March 18, 1918. Serial No. 223,101.

To all whom it may concern:

Be it known that I, JOHN F. STANDISH, a citizen of the United States, residing at Winthrop, in the county of Suffolk and State 5 of Massachusetts, have invented certain Improvements in Heeling-Machines, of which the following description in connection with the accompanying drawings, is a specification, like reference characters on the drawings indicating like parts in the several 10 figures.

This invention relates to heeling machines and is directed more particularly to improvements in the pressure mechanism of machines of the type illustrated by Letters Patent No. 884,513, granted April 14, 1908, upon the application of Benjamin F. Mayo, although it will be apparent that various features of the invention are not limited in 15 their utility to embodiment in this particular type of machine but are equally applicable to heeling machines of other types.

The general object of the invention is to improve and simplify the construction of 20 heeling machines in such respects as to permit them to be run very rapidly with a minimum of shock and wear upon the parts and at the same time to produce work of the highest quality.

The machine disclosed in the Mayo patent above referred to has been very successful, commercially, and many hundreds of them are in use in shoe factories. In that machine, however, the pressure applied to the 25 work before and during the driving of the attaching nails is transmitted through heavy springs at the sides of the machine. This pressure increases in a predetermined ratio as the nails are being driven, and the mode 30 of application of the pressure cannot be altered to suit the requirements of various classes of work. Consequently, the pressure is applied in exactly the same way whether the heels are high or low or whether 35 they are soft or hard.

Another difficulty which has been encountered in the use of the machine referred to occurs when the pressure is being released from the shoe. The side springs are very 40 heavily compressed during the nail driving operation, and as soon as the crank has passed dead center the springs expand very suddenly, causing the crank shaft to run

ahead of the balance wheel, this being possible by reason of the fact that the driving power is transmitted from the balance wheel 55 to the crank shaft through a Horton clutch. This sudden movement causes considerable shock to the machine, frequently sufficient to interfere with the proper working of the nail distributor and sometimes even sufficient 60 to throw the top lift out of the top lift holder. Furthermore, it is necessary to use a very powerful brake on the crank shaft to insure that it shall stop at the right point. This brake, being applied continuously, absorbs 65 a great deal of power and its parts wear away rapidly.

With these conditions in view, an important feature of the present invention consists in the elimination from the pressure 70 mechanism of a heeling machine of the usual springs and the provision of pressure transmitting means, preferably frictionally operated, which will not cause a rebound when the driving crank passes its dead center 75 point. With this arrangement, the pressure may be applied in the same way as in the earlier machine, but released more gradually, with the consequent elimination of the objectionable shock, and means, constituting 80 a further feature of the invention, may be associated with the friction pressure applying mechanism for permitting preliminary adjustments to determine how the pressure shall be applied. If a preferred form of the 85 invention, provision is made for either applying the pressure in a progressively increasing degree as the nails are driven, or, as is desirable in some classes of work, applying initially practically the entire amount of 90 pressure and then maintaining the pressure substantially constant throughout the nail driving operation. This result may be advantageously accomplished by the provision of means for progressively increasing the 95 friction in the pressure transmitting devices, constructed and arranged for adjustment to vary the rapidity with which the friction is increased, or even to maintain the friction constant throughout the period of pressure 100 application. This means may conveniently take the form of a cam arranged to control the frictional mechanism, and, preferably, adjustable to cause an increase in the friction in said mechanism or to cause it to re- 105

main constant while the pressure is being applied to the work. The frictional power transmitting connections or devices may include a friction drum and a band surrounding and bearing upon the drum, the arrangement being such that the adjustable cam previously referred to, operates to control the pressure of the band upon the drum. One end of the band may be anchored, while the other is yieldingly drawn in the direction of rotation of the drum when applying pressure to the work with the consequent advantage that the amount of friction upon the drum will be greater when the latter is moving in the pressure applying direction than when it is moving in the opposite direction. The necessary power for applying pressure to the work may thus be transmitted while an undue absorption of power and wearing of the parts is avoided in the idle return stroke.

In accordance with a further feature of the invention, the friction controlling cam may be thrown out of operation entirely, the band upon the friction drum being solely under the influence of a spring, the tension of which may be adjusted, but which is normally constant in the operation of the machine. In this connection an important feature consists in the particular arrangement of the friction band in its relation to the drum. One end of the band is anchored at a point which is stationary relatively to the axis of the drum while the other end is secured under tension in a yielding manner, with the result that rotation of the drum in one direction tends to draw the band closely into engagement with it, producing a substantial degree of friction, while reverse rotation of the drum causes the other end of the band to yield and the amount of friction to be reduced.

A still further feature of the invention consists in the provision of automatic means for adjustably determining the initial relative position of the drivers and the nailing die without affecting the point to which the drivers shall be moved in the nail driving operation. In the type of machine under consideration, the drivers remain continuously in the holes in the nailing die, and this adjustment provides for varying the depth of the holes to suit nails of different lengths without varying the amount of the nail which shall be left projecting from the heel when the heel is attached. I have met this condition by providing adjustable stops for variably limiting the return movement of the die, in combination with a lost motion connection between the drivers and the die, so constructed and arranged that the actuation of the drivers may be positive, but the die is permitted to stop at any desired point in its return stroke.

65 In another of its aspects, the invention re-

lates to the provision of improved means for controlling the relative approach of the jack and nailing die of a heelning machine in the successive operations of attaching a heel to a shoe and applying a top lift to the attached heel. In the machine of the Mayo patent previously referred to, the thickness of the top lift and the so-called spanking plate upon which it is supported, is compensated for by automatically operated toggle mechanism which is shown and described in detail in Letters Patent No. 446,383, granted Feb. 10, 1891, upon the application of C. W. Glidden and A. D. Elliott. In that machine, the shifting of the toggle at the back of the machine to compensate for the top lift and spanking plate is effected automatically upon the downward movement of the nailing die and drivers and operates upon the jack and its supporting mechanism. The parts which are moved are quite heavy, and the sudden movement in shifting the jack from heel attaching to top lift spanking position, or vice versa, jars the entire machine to an objectionable extent. A feature of the present invention consists in the provision of means for eliminating the sudden movement of these heavy masses of metal with the consequent vibration or jarring of the machine, and the entire compensating mechanism is greatly simplified in operation and cheapened in cost of construction. In accordance with this feature of the invention, the pressure applying member which is moved to compensate for the thickness of the top lift and spanking plate—in the present example the nailing die—has imparted to it a movement to one extent for applying pressure to the work during the heel attaching operation and to another extent for applying the pressure during the top lift spanking operation. This member may be driven by power means having an invariable stroke with the provision of automatic mechanism interposed between the power means and the pressure applying member for varying the amount of movement of the said member. In the embodiment of the invention hereinafter described and illustrated in the accompanying drawings, a lost motion connection is provided between the driver toggle and the nailing die in combination with means for eliminating the lost motion in alternate cycles of operation. This last-mentioned means may conveniently consist of an oscillating pressure supporting member having steps of different height and operated by a cam upon one of the toggle members. In this connection, a further feature of the invention consists in the provision of means for throwing the compensating mechanism out of action, and giving the pressure applying members a uniform stroke for every operation when it is desired to use the machine for surface nailing.

These and other features of the invention will best be understood from the following detailed description of one embodiment thereof to be read in connection with the 5 accompanying drawings, in which—

Figure 1 is a view in side elevation of a heeling machine embodying the invention;

Fig. 2 is a front elevation of the machine shown in Fig. 1;

10 Fig. 3 is a vertical, sectional view of the compensating mechanism;

Fig. 4 is a view in side elevation, showing particularly the frictional power transmitting connections in the pressure mechanism.

15 Figs. 5, 6 and 7 are perspective views of details of the compensating mechanism;

Figs. 8 and 9 are views in side elevation of the compensating mechanism showing it in the two extreme positions assumed 20 during the heel attaching operation; and

Figs. 10 and 11 are similar views of the same mechanism in the corresponding positions assumed in the top lift spanking operation.

25 In the drawings, 10 indicates the frame of a heeling machine and 12 indicates the jack or shoe support which is normally stationary vertically, but may be adjusted in accordance with the thickness of the work 30 to be operated upon.

Power is furnished to the machine by a continuously running balance wheel 14 which is connected through the usual one-revolution Horton clutch with the crank 35 shaft 16. The crank shaft is connected by a connecting rod 18 to the center of a toggle comprising a link 20 pivoted at 22 to the machine frame, and a link 24 pivoted at 26 to a spindle 28 which carries, at its upper 40 end, a gang of nail drivers 30.

The nailing die 32 is mounted in a die support 34 rigidly connected to the upper ends of a pair of upright rods 36. The rods 36 are guided for vertical movement in 45 sleeves 38, the upper ends of which are secured by clamping members 40 to the driver head 42 carried at the upper end of the die bed spindle 28. Rack teeth 44 are formed in the rods 36 and pinions 46 meshing with the rack teeth are formed upon 50 shafts 48 to each of which is keyed a friction drum 50.

Inasmuch as the two sides of the pressure applying mechanism are symmetrical 55 with respect to each other, it will be sufficient to describe one of them in detail. The lower end of the rod 36 is reduced, as shown at 52, and passes through a guiding bushing 54, which is treaded to permit vertical adjustment in a bracket 56 secured to the machine frame by bolts 58. A set screw 60 is provided for securing the bushing in adjusted position. A washer 62 of yielding shock absorbing material surrounds the reduced portion of the rod, resting against the

shoulder formed at the junction of the main portion 36 of the rod and its reduced portion 52.

The friction drum 50 is provided with flanges 64 for the purpose of maintaining in 70 proper relation to the drum a friction band 66, one end of which is anchored on a pin 68 mounted in a bracket 70, bolted to, or formed integrally with, the sleeve casting 38. The anchor pin 68 is located beneath, 75 and substantially in vertical alinement with, the axis of the friction drum. The friction band 66 is lined with leather or other suitable friction material 72 and partially encircles the drum, engaging its periphery. 80

A bell crank lever 74 is pivoted at 76 to the rear end of the bracket 70, and a rod 78 attached to the free end of the friction band 66 passes loosely through a hole in the end of a forwardly extending arm 80 of the 85 lever. A compression spring 82 surrounds the lower end of the rod 78 and the ends of the spring bear respectively against the end of the arm 80 and a nut 84 threaded upon the lower end of the rod 78, by adjustment of which the tension of the spring may be varied. The end of a screw 86 passing through the lever arm 80 bears against the friction band where the latter surrounds the anchor pin 68, and this screw may be 90 adjusted to vary the limit of upward movement of the arm.

The second arm 88 of the bell crank lever 74 extends downwardly and a roll 90 is mounted in its lower end. The roll is arranged to engage an adjustable cam, comprising a plate 92 secured to the machine frame by screws 94 passing through slots 96 in the plate, and an angularly adjustable cam member 98 pivoted to the plate 92 by a 100 screw 100 and secured in adjusted position by a bolt 102 passing through a slot 104 in the member 98 and threaded into the plate 92. It will be apparent that this construction provides for bodily adjustment of the 105 entire cam structure vertically and independent angular adjustment of the cam member 98 about the pivot 100. A straight vertical surface, to be engaged by the roll 90, is formed upon the rear face of the cam plate 92 and a corresponding cam surface 108 is formed upon the rear face of the cam member 98. The lower end of the member 98 is formed as a pointer 110, coöoperating with a graduated scale 112, the purpose of 110 which is to facilitate a like adjustment of the cam members 98 upon the two sides of the machine, in order that the two friction bands 66 may be operated simultaneously in exactly the same way.

The mechanism for compensating for the thickness of the top lift and spanking plate will now be described, after which the operation of the machine will be described in proper sequence. As already stated, the con- 130

necting rod 18, which transmits motion from the crank shaft 16 to the toggle 20, 24, has an invariable movement and is connected to the center pivot 114 of the toggle. A rocker member 116 is rigidly secured to a rock shaft 118 by a pin 120 (see Fig. 5). The rock shaft 118 is mounted for oscillatory movement in the upper toggle link 24. A curved pressure supporting surface or step 122 is formed upon the rocker member 116, being arranged to engage a complementary curved surface 124 upon the lower face of a yoke 126, having a tongue and groove connection 128, by virtue of which the yoke is permitted to slide longitudinally in the upper end of the link 24. The curved surface 124 is formed on an inwardly extending portion 130, which also has formed in its upper face an extended bearing for the upper toggle pivot 26 (see Fig. 3). By this arrangement a solid train of connections is secured for transmitting the necessarily great force to the nailing die and drivers.

A spring pressed plunger 132, located in a recess in the member 116 and bearing upon a rearwardly extending bracket 134 formed as a part of the toggle link 24 tends always to swing the member 116 forwardly into the position illustrated in Figs. 3, 4, 8 and 9. This is the position occupied by the parts during the operation of driving the nails to attach the heel to the shoe.

A screw 136 having its upper face curved to correspond to the surface 122 is threaded into the member 116, as shown clearly in Fig. 5. The member 116 is split and provided with a clamping bolt 138 for securing the screw 136 immovably in position when the desired vertical adjustment of the screw has been secured. The function of the screw 136 is to transmit the working pressure when the top lift is being attached to the heel, and it is normally so adjusted that its curved face is below the surface 122 by a distance equal to the thickness of the top lift and the spanning plate interposed between the nailing die and the heel. During the top lift spanning operation, the rocker member 116 occupies the angular position relatively to the toggle link 24, shown in Figs. 10 and 11. By virtue of a lost motion connection consisting of slots 140 in the upper end of the link 24 where the pin 26 passes through it, the pressure transmitting screw or step 136 is permitted to rise from the position shown in Fig. 10 to that shown in Fig. 11 where the top of the screw engages and transmits pressure to the member 130. It will be observed that the member 130, which is movable loosely for a short distance vertically, acts as an interponent between either the step 122 or 136, and the pin 26, which is rigidly mounted in the lower end of the spindle 28.

For the purpose of swinging the rocker

member 116 from one position to the other the following mechanism is provided. A collar 142 is rigidly secured to the rock shaft 118, and the outer end of the shaft is reduced to form a trunnion for a hub 144 carrying an arm 146 provided at its outer end with a roll 148. Tongues 150 formed on the end of the hub 144 are arranged to enter slots 154, in the collar 142. A spring 158 located in a recess in the hub and held in position by a washer 160 and nut 162 upon the end of the rocker shaft 118 tends to hold the hub in locking engagement with the collar, but permits the hub to be drawn outwardly and turned upon the shaft 118 into a different angular relation to the shaft, where the tongues 150 may enter the slots 154 and lock the arm 146 in an inoperative position.

A cam member 164, having three identical cam faces 166, is formed on the face of a disk 168 which is journaled to rotate on the end of the center toggle pin 114. Ratchet recesses 170 are formed in the inner face of the disk 168 and spring pressed pawls 172, 174 mounted respectively in the toggle links 24, 20 are arranged to engage in the recesses to rotate the disk and cam relatively to the pin 114 when the toggle links are moved angularly relatively to each other. The spring pressed plunger 132 keeps the roll 148 in engagement with the cam 164 and it will thus be apparent that the cam constitutes controlling means for determining which of the steps 122, 136 shall be in pressure transmitting relation to the member 130.

The operation of the above described machine is as follows: Assuming the machine to be in the position of rest, as illustrated in Figs. 1 and 2, with the rocker member 116 in the position shown in Fig. 8, a load of nails is deposited in the nailing die 32, a heel is placed in position upon the die, and a shoe is jacked and swung in over the heel. The clutch is then tripped and the crank shaft executes one revolution. Inasmuch as the stopping position of the crank is practically upon its rear dead center point, the first half of its revolution produces forward movement of the connecting rod 18 until the toggle 20, 24 is straightened. Assuming the position shown in Figs. 4 and 9, inasmuch as the high step 122 is under the pin 26, the lost motion connection 140 is inoperative upon this stroke and the spindle 28 is given a positive upward movement throughout the entire period of the forward stroke of the connecting rod. The cam 98 may be so adjusted that the roll 90 is initially in engagement with the straightaway portion of the plate 92, and the nut 84 adjusted to produce sufficient tension upon the spring 82 to draw the friction band 66 into engagement with the drum 50, producing enough friction between the band and the drum to prevent ro-

tation of the drum until the nailing die encounters resistance to its upward movement. Under these conditions, the spindle 28 and driver head 42 will carry the side rods 36 5 and nailing die 32 upwardly until the heel upon the nailing die engages the shoe. At this point, the resistance of the shoe and heel to further upward movement of the nailing die will tend to cause the friction 10 drum 50 to be rotated by relative movement of the rack 44 and pinion 46. Such rotation of the friction drum will be resisted by the friction band 66 to an extent dependent upon the tension of the spring 82 and sufficiently to exert pressure upon the work during 15 the continued upward movement of the spindle 28.

At about the time when the heel engages the shoe, the roll 90 will begin to ride rearwardly upon the inclined cam face 108, thereby progressively increasing the friction of the band 66 upon the drum 50 during the further upward movement of the spindle and consequently increasing progressively 25 the pressure applied to the work while the nails are being driven. When the resistance to the movement of the nailing die becomes sufficient, the drum 50 will slip in the band, and the drivers 30 will move 30 upwardly through the nailing die, driving the attaching nails through the heel into the shoe.

As the connecting rod 18 starts upon its 35 rearward stroke, the toggle 20, 24 is broken and the spindle 28 moves downwardly. The initial portion of this downward movement releases the pressure from the work and is unresisted until the washers 62 engage the upper ends of the bushings 54, whereupon 40 downward movement of the rods 36 and the nailing die supported thereby is stopped and the continued descent of the spindle 28 with the driver head 42 and sleeves 38 carried thereby, will produce a reverse rotation of 45 the friction drum 50 in a clockwise direction, as viewed in Fig. 4. Prior to the engagement of the washer 62 with the bushing 54, the roll 90 arrives upon the straigtaway portion of the plate 92, materially diminishing 50 the tension upon the spring 82. Furthermore, the spring 82 is quite light and yields readily, with the result that frictional resistance to the rotation of the drum 50 in the direction in which it is moving at this 55 time is very small. Thus an unnecessary absorption of power in restoring the parts to their initial positions is avoided.

During the breaking of the toggle 20, 24 and the downward movement of the spindle 28, the pawl 174 operates to rotate the disk 168 from the position shown in Figs. 8 and 9 to that shown in Figs. 10 and 11, the roll 148 riding up on the face 166. The arm 146 is thus actuated automatically

to swing the rocker member 116 from heel 65 attaching to top lift attaching position, with the step 136 in alinement with the member 130.

In the next cycle of operation of the machine, the initial portion of the forward 70 movement of the connecting rod 18 will be ineffective until the lost motion permitted by the slot 140 is taken up, and the step 136 engages the surface 124. In this cycle of the 75 operation of the machine, therefore, the extent of upward movement of the spindle 28 will be less than that in the heel attaching operation by an amount equal to the difference in the heights of the two steps 122 and 136—that is to say, by an amount sufficient 80 to compensate for the added thickness of the top lift and spanking plate, introduced between the heel and the nailing die prior to the starting of the machine for the top lift spanking operation.

It will be apparent from the preceding detailed description of the mechanism of the machine that provision is made for adjustably varying the operation of the machine to suit all classes of work. By vertical adjustment of the cam plate 92, the point in the nail driving operation at which the roll 90 begins to ride upon the inclined cam face 108 may be varied to cause the progressive increase of pressure upon the work to begin 95 at any desired time, and the swinging adjustment of the cam member 98 about the pivot 100 permits the rate of the progressive increase of the friction between the drum 50 and the band 66, and consequently the 100 rate of progressive increase of pressure upon the work, to be varied, as desired. On the other hand, in some classes of work it may be desired to apply a certain amount of pressure to the work and to maintain that 105 pressure constant throughout the nail driving operation. Under these conditions, the cam member 98 may be swung to the left, as seen in Fig. 4, until its face 108 is practically a continuation of the straightaway face of 110 the plate 92, whereupon the friction in the power transmitting connections will remain constant throughout the stroke of the spindle 28 but may be adjusted by turning the nut 84 to change the tension of the spring 115 82. If it be desired to produce greater friction than can be secured by adjustment of the nut 84 the screw 86 may be turned through the arm 80 until the roll 90 is lifted away from its cam, whereupon a constant 120 amount of friction will exist between the drum and band during the upward stroke. The amount of this friction, however, will be very much less on the return stroke by reason of the yielding of the spring 82, as 125 previously described.

The operation of the machine has been described above as it occurs when attaching

first a heel and then a top lift in so-called blind nailed work. In surface nailed work, however, the heel and top lift or the heel with the top lift previously attached to it is attached to the shoe by a single nailing with a single stroke of the spindle 28, and under these circumstances alternate movements of the nailing die to different extents are not desired. To meet this condition, it is merely necessary to draw the hub 144 outwardly against the tension of the spring 158, turn it angularly forward until the tongues 150 are in alinement with the grooves 154, and release it, whereupon the arm 146 will be locked in an inoperative position in which the roll 148 will not be engaged by the cam 166. The spring pressed plunger 132 will now maintain the rocker member 116 continuously in heel attaching relation to the toggle, and the operation of the machine will proceed as with a simple toggle, a uniform stroke being imparted to the spindle 28 in successive cycles of operation.

Having thus described my invention, what I claim as new and desire to secure by Letters Patent of the United States is:—

1. In a heeling machine, the combination of a work engaging member, power operated means for actuating the said member, yielding power transmitting connections between the actuating means and the member, and means for preliminarily adjusting the connections to transmit the pressure in a variable manner during the application thereof.

2. In a heeling machine, the combination of a work engaging member, power operated means for actuating said member to apply pressure to the work, yielding power transmitting connections between the actuating means and the member, and preliminarily adjustable means for varying during the application of pressure the resistance of said yielding connections.

3. In a heeling machine, the combination with a work engaging member, power means for actuating said member to apply pressure to the work, yielding friction power transmitting connections between the actuating means and the member, and preliminarily adjustable means for varying during the application of pressure the friction in said connections to regulate the application of pressure to the work.

4. In a heeling machine, the combination of a work engaging member, power operated means for actuating said member, frictional power transmitting connections between the actuating means and the member, and means for insuring a progressive increase of the friction in said connections while the pressure is being applied to the work.

5. In a heeling machine, the combination of a work engaging member, power operated means for actuating said member to apply

pressure to the work, frictional power transmitting connections between the actuating means and the member, and controlling mechanism for the frictional means preliminarily adjustable at the will of the operator to cause the friction to be progressively increased or to remain constant, as desired, during the application of pressure to the work.

6. In a heeling machine, the combination of a work engaging member, power operated means for actuating said member to apply pressure to the work, yielding power transmitting connections between the actuating means and the member and controlling mechanism preliminarily adjustable at the will of the operator to modify the action of said yielding connections to cause the pressure either to be progressively increased or to remain constant throughout the period of its application to the work.

7. In a heeling machine, the combination of a work engaging member, means for moving said member to apply pressure to the work, and frictional power transmitting mechanism between said means and member embodying a friction drum, a band bearing upon said drum, and means for keeping the band under tension.

8. In a heeling machine, the combination of a work engaging member, means for moving said member to apply pressure to the work, and frictional power transmitting mechanism between said means and member embodying a friction drum, a band bearing upon said drum, and means acting in the operation of the machine for varying the pressure with which the band bears upon the drum.

9. In a heeling machine, the combination of a work engaging member, means for moving said member to apply pressure to the work, and frictional power transmitting connections between said means and member including a friction drum, a band bearing upon said drum and means for increasing the pressure of the band upon the drum during the application of pressure to the work.

10. In a heeling machine, the combination of a work engaging member, means for moving said member to apply pressure to the work, and power transmitting connections between said means and member, including a friction drum, a band bearing on said drum and a cam for controlling the action of the band upon the drum.

11. In a heeling machine, the combination of a work engaging member, means for moving said member to apply pressure to the work, pressure transmitting connections between said means and member including a friction device, and a cam movable into and out of controlling relation to the friction device.

12. In a heeling machine, the combination of a work engaging member, means for moving said member to apply pressure to the work, pressure transmitting connection between said means and member, including a friction device, and an adjustable cam for variably controlling the operation of the friction device.
13. In a heeling machine, the combination of a work engaging member, means for moving said member to apply pressure to the work, and power transmitting connections between said means and member including a friction device movable in two directions and constructed and arranged to operate with greater friction when moving in one direction than when moving in the other direction.
14. In pressure mechanism for heeling machines, the combination of a pressure member arranged for coöperation with the work, and operating connections therefor including a rotatable, reversible friction drum, and a friction band partially surrounding and bearing upon the drum, one end of the band being anchored at a point which is stationary relatively to the axis of the drum, and the other end of the band being held yieldingly under tension, whereby greater friction is exerted upon the drum during its rotation in one direction than during its rotation in the opposite direction.
15. In pressure mechanism for heeling machines, the combination of a pressure member arranged for coöperation with the work, and operating connections therefor, including a rotatable, reversible friction drum, a friction band partially surrounding and bearing upon the drum, one end of the band being anchored at a point which is stationary relatively to the axis of the drum, a spring connected to the other end of the band and arranged to draw the band into engagement with the drum and means for varying the tension of the spring.
16. In a heeling machine, the combination of a nailing die, reciprocating nail drivers, means for advancing the drivers and die, and automatic means for variably limiting the return stroke of the die without affecting the stroke of the drivers.
17. In a heeling machine, the combination of a nailing die, reciprocating nail drivers, means for advancing the drivers to a fixed, predetermined limit and the die through a less distance, said advancing means acting also to withdraw the drivers and die, and means for variably limiting the return stroke of the die.
18. In a heeling machine, the combination of a nailing die, reciprocating nail drivers, means for advancing the drivers to drive nails, a lost motion connection between the drivers and the die, an adjustable stop for variably predetermining the limit of the re-
- turn stroke of the die, and means for setting the stop in the operation of the machine.
19. In a heeling machine, the combination of a reciprocable nailing die, a reciprocating driver spindle, a gang of nail drivers mounted upon the spindle, power means for advancing the spindle to drive nails, lost motion connections between the spindle and the die arranged to move said die in opposite directions, and an adjustable stop for variably limiting the return stroke of the die.
20. In a heeling machine, the combination of a driver supporting head, a gang of nail drivers carried by the head, power means for advancing the head and drivers to drive nails, an upright sleeve rigidly secured to the head, a reciprocable guide rod within the sleeve, a nailing die supported by the guide rod, and an adjustable bushing surrounding the guide rod beneath the sleeve, said bushing being in position to be engaged by the rod to limit the return stroke thereof.
21. In a heeling machine, the combination of a stationary work engaging member, a movable member for engaging and exerting pressure upon the work, power means having an invariable stroke for actuating the movable member, automatically acting mechanism for varying the limit of the advancing movement of the movable member, and means for rendering said automatically acting mechanism inoperative.
22. In a heeling machine, the combination of relatively movable work engaging and pressing members, power means having an invariable stroke for actuating one of said pressing members, automatically acting mechanism for varying the limit of the advancing movement of said member, and means for rendering said automatically acting mechanism inoperative.
23. In a heeling machine, the combination of a jack, a nailing die, means for advancing the nailing die toward the jack to exert pressure upon the work, controlling mechanism acting automatically to cause the nailing die to be advanced alternately to greater and less distances from the jack in successive cycles of operation of the machine and means for rendering said controlling mechanism inoperative.
24. In a heeling machine, the combination of a jack, a nailing die, toggle mechanism for moving the nailing die toward the jack to exert pressure on the work, and means acting automatically to transmit alternately greater and less amounts of the movement of said toggle mechanism to the nailing die in successive cycles of operation of the machine.
25. In a heeling machine, the combination of a jack, a nailing die, toggle mechanism for moving the nailing die toward the jack to apply pressure to the work, and automatic means controlled by the movement of

the toggle for causing alternately greater and less proportions of the throw of the toggle to be transmitted to the nailing die.

26. In a heeling machine, the combination 5 of a jack, a nailing die, toggle mechanism for effecting relative approaching movement of the nailing die and the jack to apply pressure to the work and automatic means carried by the toggle for causing alternately greater and less proportions of the 10 throw of the toggle to be transmitted to the die in successive cycles of operation of the machine.

27. In pressure mechanism for heeling 15 machines, the combination of a nailing die, means for supporting the die, toggle mechanism for advancing the die and die support, and a rocker member mounted in one link of the toggle, said rocker member having steps of different heights alternatively movable into position to transmit the movement of the toggle to the die support.

28. In pressure mechanism for heeling 20 machines, the combination of a nailing die, toggle mechanism for advancing the die to apply pressure to the work, a member car-

ried by the toggle and having steps of different heights movable alternatively into position to transmit the movement of the toggle to the die, automatic means for effecting said movement of said member, and means for rendering said automatic means inoperative.

29. In pressure mechanism for heeling 30 machines, a pressure toggle embodying a 35 rocker member having pressure transmitting portions of different heights, cam mechanism for moving said pressure transmitting portions alternatively into operative position and ratchet mechanism operated by 40 relative movement of the toggle links for actuating said cam mechanism.

30. In a heeling machine, the combination 45 of a nailing die, toggle mechanism for advancing the die to apply pressure to the work, a lost motion connection between the toggle and the nailing die, and means for eliminating the lost motion in alternate cycles of operation of the machine.

In testimony whereof I have signed my 50 name to this specification.

JOHN F. STANDISH.
